UNITED STATES PATENT OFFICE.

GEORGE O. NIGHSWANDER, OF KANSAS, OHIO.

SPARK-PLUG.

1,361,347.

Specification of Letters Patent. Patented Dec. 7, 1920.

Application filed December 8, 1919. Serial No. 343,204.

To all whom it may concern:

Be it known that I, GEORGE O. NIGHSWANDER, a citizen of the United States, residing at Kansas, in the county of Seneca 5 and State of Ohio, have invented a new and useful Spark-Plug, of which the following is a specification.

This invention relates to new and useful improvements in spark plugs, and the object of the invention is to generally simplify the construction of spark plugs and to provide novel means whereby the points of the electrodes will be kept clean so as to prevent inoperation due to the collection 15 of carbon on the same.

A further object of the invention is to provide a spark plug arranged to receive the gas through the casing thereof and having novel electrode points, one of which 20 is designed to be operated during the compression and exhaust of the motor, for the purpose of cleaning the points.

With the above and other objects in view which will appear as the description proceeds, the invention resides in the combination and arrangement of parts and in the details of construction hereinafter described and claimed, it being understood that, within the scope of what is claimed, changes in 30 the precise embodiment of the invention shown can be made without departing from the spirit of the invention.

In the accompanying drawings:

Figure 1 is a vertical sectional view showing my improved spark plug; and

Fig. 2 is a detailed cross sectional view thereof.

Referring to the drawings in detail, in which like reference characters indicate corresponding parts throughout the several views, my improved spark plug is shown as comprising a casing or shell 10 having an inwardly offset or reduced portion 11 provided with external threads 12 by means 40 of which the same can be secured to a cylinder of an internal combustion engine. There is thus provided an oppositely facing shoulder 13 adapted to be contacted by an annular rim 14 circumscribing the tapered 45 bushing of smaller diameter than the interior of the casing, so as to receive a securing nut 16 which has interior threaded engagement with the casing 10 in order to secure the bushing in position.

50 There extends through an axial opening

in the bushing, a positive electrode 17, the end portion 18 of which is threaded in the usual manner for receiving a binding nut and for connection with the current conducting wire. This terminal extends 60 through the inner portion of the bushing, which is tapered as indicated at 19 in an opposite direction to the direction of taper of the bushing portion 15, and also formed with an enlarged socket or opening 20, the point of the electrode 17 extending slightly beyond the tapered end of the end portion 19. The reduced portion 11 of the casing or shell is provided with series of openings therethrough as indicated at 21, and is 65 formed at the bottom with inturned flanges 22 designed to retain a flat electrode 23 in position. This electrode is in the form of a plate and is adapted to have play between the flanges and the point of the terminal electrode 17, so as to effectively clean the points, owing to the reciprocation of the plate 23, from the compression and exhaust of the gases within the cylinders to which it is applied. It is to be understood that the spark 70 gap is formed between the electrode 17 and the electrode 23 when the latter is in position, retained against displacement by the flanges 22, so that the circuit is grounded 75 to the body of the plug and to the cylinder. 80

In use, the gases pass through the openings 21 and into the shell, so that when the current is passed through the electrodes at the proper time, a spark takes place between the points 17 and 23, so as to ignite the gases 90 in the cylinder. As the compression takes place, the plate 23 is forced upwardly, and the sparking action may take place immediately after the compression has been released, in order to permit explosion of the 95 gases at the proper time. Thus, the continual vibration or reciprocation of the plate 23 will effectively clean the points and retain them in operative condition. It will also be seen that the formation of the inner 100 end of the bushing produces a firing chamber between it and the inner wall of the casing at the attaching end thereof, so that as the gases escape into this chamber through the openings 21, an effective firing of the 105 gases is rendered possible, the spark igniting the gases and communicating the same to the cylinder around the electrode 23, owing to the same being of smaller diameter than the interior diameter of the casing at its at- 110

taching portion 11. Also, the flange 22 will effectively retain the spark point electrode 23 against displacement.

Having thus described the invention, what I claim is:

1. A spark plug comprising a body including an attaching casing, a bushing mounted in the casing, means to retain said bushing in position, a positive electrode extending through the bushing and forming a sparking point, said bushing forming an opening within the body and casing thereof, the lower end of the casing being formed with a flange extending inwardly to provide a central opening, and a second electrode in the form of a plate mounted in the casing and retained from displacement by said flange, said plate being unattached and cooperating with the first named electrode.
- 15 2. A spark plug comprising a casing having an offset portion providing a shoulder,
- 20 2. A spark plug comprising a casing having an offset portion providing a shoulder,

a bushing having an angular rib engaging said shoulder, retaining means engaging the casing to secure the bushing in position, said bushing having inwardly tapering end and an opening around the same, a terminal electrode extending through the bushing, a flange at the inner end of the casing, said casing having openings therethrough and a second electrode forming point, said electrode being in a form of disk or plate of smaller diameter than the interior diameter of the casing and movable between the first mentioned point and said flange, as for the purposes specified.

In testimony that I claim the foregoing as my own, I have hereto affixed my signature in the presence of two witnesses.

G. O. NIGHSWANDER.
